COMB

August L. Voight, Berea, Ohio

Application October 2, 1947, Serial No. 777,453

1 Claim. (Cl. 132—24)

1

This invention relates to a new and improved comb and particularly to a comb used to form a roll of hair upon a woman's head.

An object of the invention is to provide a comb for forming a roll of hair upon a woman's head and which is efficient in use and easy to apply and remove.

Another object is to provide a comb as specified in the above object and which when applied is hidden from view by the roll of hair it forms.

A further object is to provide a comb as above referred to and which has improved and novel means for holding itself in applied position in the roll of hair.

A still further object is to provide a comb as above referred to and which when applied does not become ensnared in the hair and can be readily removed.

A still further object is to provide a comb as above specified and which during application can be straightened to facilitate the operation and after it has been fully applied and the user releases his grasp upon the opposite ends of the comb the latter will automatically conform to the shape of the user's head.

Further and additional objects and advantages not hereinbefore referred to will become apparent during the detailed description which is to follow.

The invention contemplates a comb having a body or strip portion from which extends a series of straight teeth while said strip has integrally formed therewith a cylindrical portion or portions projecting laterally of the strip and if two such portions are employed they are located preferably adjacent the opposite ends of the strip. The cylindrical portion or portions function to form a roll of hair upon the side of a woman's head or a roll of hair on the back of the head generally referred to as a "chignon." The series of straight teeth function to retain the comb in the hair after the roll has been formed.

In forming the roll the hair does not extend interiorly of the cylindrical portion or portions but rolls around the exterior of said portion or portions. Therefore the comb may be readily removed when desired since no part of the comb is ensnared in the hair, it being understood that the straight teeth can be readily withdrawn from the hair. Preferably the straight teeth adjacent the opposite ends of the body strip are more closely spaced together than are the teeth intermediate the ends of the body strip. This further facilitates the insertion and withdrawal

2

of the comb since the hair wrapped around the thin body strip might bind or snarl if the teeth intermediate the cylindrical portions were closely spaced.

5 The comb is so constructed that it will be entirely hidden from view when applied by the roll of hair surrounding the cylindrical portions and by the relatively straight hair in which the straight retaining teeth are located.

10 The comb may be conveniently formed from suitable material such as plastic and it is proposed to embed in the cylindrical portions, at least on combs designed for use on the rear of the head, a curved metal spring, whereby the user in applying the comb can by grasping and moving its opposite ends straighten the comb and then upon releasing said opposite ends the comb will conform to the shape of the user's head.

15 20 Referring to the accompanying drawing illustrating an embodiment of the invention,

Fig. 1 is a top plan view of the comb, its normal configuration being indicated by full lines and its straightened configuration being indicated by dot and dash lines.

25 Fig. 2 is an elevational view of the comb.

Fig. 3 is a diagrammatic illustration of the initial position of the comb in using it to form a roll of hair.

30 Figs. 4 and 5 are diagrammatic illustrations of two intermediate positions of the comb during its use to form a roll of hair, and

35 Fig. 6 is a diagrammatic illustration of the final position of the comb after the roll of hair has been formed and the comb completely applied to the head.

The comb comprises a body or strip 10 which may be straight or curved depending upon whether the roll to be formed by the comb is 40 on the side or on the back of the head. The comb illustrated, for purposes of explanation, is a curved comb and is suitable for forming a chignon upon a woman's head. In the curved form of comb a curved metal spring strip 11 preferably is embedded in the cylindrical portions 45 at the opposite ends of the strip and extends therebetween above the upper edge of the strip, wherefore the user of the comb may straighten the comb as indicated by dot and dash lines in Fig. 1 in applying the comb to the hair and then when applied release the straightened comb to allow it to resume its curved configuration and to conform to the shape of the head.

The body or strip 10 has depending from its 50 lower edge a series of straight teeth 12 which

are integral with the body or strip and have in a direction longitudinally of the strip the same curvature as the body or strip. The series of straight teeth 12 may be designated as retaining teeth and if desired could be in the form of what is known in the art as "gripper" teeth. It will be noted that the straight teeth 12 adjacent the opposite ends of the body or strip are relatively closely spaced while intermediate the ends of the body or strip said teeth are more widely spaced, the spacing between the teeth gradually increasing toward the middle point of the body or strip.

The body or strip 10 also has integrally formed therewith a cylindrical portion or portions 13 extending above the upper edge of the strip and projecting laterally from the side of the strip and merging with both longitudinal edges of the strip. The illustrated form has two such cylindrical portions located at the opposite ends of the strip. The cylindrical portions 13 preferably have their opposite ends formed convergently in a direction away from the strip with the outer side of the portions curved concentrically to the curvature of the strip. The cylindrical portions 13 may be designated as roll forming portions since they function to form the roll of hair.

The comb may be economically and efficiently made from suitable plastic material and preferably will have a certain measure of flexibility in addition to the flexibility of the metal spring 11. The flexibility of the comb and of the metal spring should be such that when it has the curved configuration from end to end as shown and described herein the ends of the comb can be slightly spread apart in applying the comb and then when released will grip the sides of the wearer's head and hold the comb in position around the back of the head.

The diagrammatic illustrations of Figs. 3 to 6 inclusive show the manner in which the comb is applied to the back of the wearer's head, it being understood that these views illustrate the hair at the back of the head.

In Fig. 3 the hair at the back of the head is shown as having been combed or brushed straight preparatory to applying the comb. The user of the comb then takes the same and spreads the ends thereof slightly apart and then positions it in the hair so the outer surfaces of the cylindrical portions 13 are engaging the hair while the straight teeth 12 are located in the hair near the ends thereof. The user then rotates the comb in the direction indicated by the arrow from its position of Fig. 3 into its position of Fig. 4. During such rotation the hair is partially formed into a roll around the cylindrical portions 13. It will be understood that this partial roll of the hair also extends between the cylindrical portions 13 and around the body or strip 10 and the spring 11. The user then continues the rotation of the comb in the direction of the arrow from the position of Fig. 4 into the position of Fig. 5, at which time the roll of hair is almost completed and the cylindrical portions 13, body 10 and spring 11 are substantially entirely within the relatively completed roll of hair, it being noted, however, that none of the hair is within the cylindrical

portions. It will also be noted by reference to Fig. 5 that at this time the straight teeth 12 are pointed angularly upwardly in the roll of hair. The user continues to rotate the comb in the direction of the arrow until the straight teeth 12 are pointing downwardly, whereupon the comb is raised slightly and then moved downwardly into the position of Fig. 6. At this time the cylindrical portions 13, body 10 and spring 11 are completely located within the roll while the straight teeth 12 extend downwardly through the hair of the roll and retain the comb in position in the roll.

It will be noted that when the comb is thus fully applied none of the hair of the roll is within the cylindrical portions 13 and therefore the hair is not ensnared in any curved portions of the comb which would hinder its removal from the roll when the user desires to do so.

It will be noted further that the entire comb is concealed by the hair and that when the user releases the ends of the comb the latter will contract due to the flexibility of the comb and will grip the sides of the head. Thus the comb together with the retaining function of the teeth 12 is maintained in position on the head.

From the foregoing it will be seen that a comb embodying the present invention can be readily and effectively applied to form a roll of hair and that when the roll has been formed the comb will be retained in position to maintain the roll and will be completely concealed by the roll of hair.

Although a preferred embodiment of the invention has been illustrated and described it will be understood that the invention is susceptible of various modifications and adaptations within the scope of the appended claim.

Having thus described my invention, I claim:

A comb comprising a body strip, a series of straight retaining teeth extending from one longitudinal edge of said body strip and more closely spaced together adjacent the opposite ends of the body strip than intermediate said ends, and spaced cylindrical portions integral with said body strip and projecting laterally from a side thereof above the attaching ends of said teeth and merging with both longitudinal edges of said body strip.

AUGUST L. VOIGHT.
